(57) **CLAIM**

The ornamental design for an a actuator for finger pump, as shown and described.

DESCRIPTION

FIG. 1 is an isometric view of my new design for a actuator for finger pump,

FIG. 2 is a front view thereof;

FIG. 3 is a top view thereof;

FIG. 4 is a right side view thereof;

FIG. 5 is a left side view thereof;

FIG. 6 is a bottom view thereof;

FIG. 7 is a cross-sectional view thereof, taken in the direction of the arrows along line 7—7 of FIG. 3;

FIG. 8 is an isometric view of a second embodiment of FIG. 1;

FIG. 9 is a front view thereof;

FIG. 10 is a top view thereof;

FIG. 11 is a right side view thereof;

FIG. 12 is a left side view thereof;

FIG. 13 is a bottom view; and,

FIG. 14 is a cross-sectional view thereof, taken in the direction of the arrows along line 14—14 of FIG. 10.
